UNITED STATES PATENT OFFICE.

MOSES MOSLER, OF CINCINNATI, AND CARL BARTELS, OF HAMILTON, OHIO, ASSIGNORS
TO THE MOSLER SAFE COMPANY, OF NEW YORK, N. Y.

SAFE-DOOR.

1,118,436.

Specification of Letters Patent.

Patented Nov. 24, 1914.

Application filed June 18, 1914. Serial No. 845,795.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Safe-Doors, of which the following is a specification.

10 In round door safes one plan of construction is to screw the door into its door-jamb and to prevent unscrewing by suitable locking devices. In such type of safe, which we will refer to as the screw door type, the door, in being screwed to the jamb, is given about one revolution and so, also, in being unscrewed from the jamb. In another plan of constructing round door safes, the door is screwed to place but the screw is of interrupted character and the helical character of the interrupted thread is so gentle that the screw feature is hardly recognizable. In this second type of safe, which we will refer to as the lug type, the door, in being seated 20 home in the door-jamb, is given but a mere fraction of a turn, and so, also, in unseating the door.

Our improved door is a compound door in which one component carries the other telescopically, one component being of screw door type and the other component being of lug type, each component having its individual lock.

Our improved door will be readily understood from the following description taken in connection with the accompanying drawings in which:—

Figure 1 is a front view of a safe fitted with our improved door, the door being shown in open position: Fig. 2 a side elevation of the door with its inner or screw-member protruded from the front member as when the door is in closed or locked position: Fig. 3 a similar side elevation of the door when the inner or screw-member is retracted into the front or lug-member of the door: Fig. 4 a front elevation of the door: Fig. 5 a rear elevation of the door: Fig. 6 a horizontal section of the door with both of its members seated, and locked into the door-opening of the safe, the section being substantially in the plane of line *a* of Figs. 2, 3, 4, 5, 8, 9 and 13: Fig. 7 a similar horizontal section with the screw-member of the door retracted into the lug-member: Fig. 8 a front elevation of the

door with a portion of the escutcheon plate broken away: Fig. 9 a front elevation of the door with the front plate of the gear-casing removed: Fig. 10 a diametrical section of a portion of the door in the plane of line *c* of Fig. 12: Fig. 11 a diametrical section of a portion of the door in the plane of line *b* of Figs. 4, 8, 9 and 13: Fig. 12 a plan of the rear portion of the screw-door, a portion of the lug-door appearing in section in the plane of line *d* of Figs. 9 and 13; and Fig. 13 a vertical section of the lug-door viewed from the rear in the plane of line *e* of Figs. 6, 7 and 10.

As the door-members are to be considered in various angular positions, such fact should not be lost sight of in considering the planes on which diametrical sections are taken in the various figures of the drawings.

In the drawings:—1, indicates the general body of the safe or vault; 2, the front wall thereof; 3, the tapering circular opening in the front wall for the reception of the circular door; 4, segmental lugs projecting inwardly from the door-opening, at some little distance back from the extreme front of the door-opening; 5, a tapering circular door adapted to fit accurately within that portion of the door-opening forward of lugs 4; 6, that portion of the door immediately in the rear of the portion 5; 7, segmental lugs projecting outwardly from the portion 6 of the door and adapted, when the door is closed, to be turned in behind the lugs 4, the contacting surfaces of the lugs 7 and 4 being slightly helical as is usual in lug door safes, so that when the door is turned the door is drawn tightly into its seat; 8, a circular gear-casing disposed at the front of the door and on which the door is concentrically journaled; 9, the hinge-crane, having as usual hinged union with the front wall of the safe; 10, pintles uniting the top and bottom of gear-casing 8 with the free arms of the hinge-crane; 11, a bearing carried by the gear-casing concentric with the axis of the door; 12, a journal secured to the front of the door and adapted to turn in bearing 11 so that the door may turn in the gear-casing; 13, a gear secured to the front of the door concentric with the axis of the door; 14, a pinion journaled in a bay formed in the gear-casing, this pinion engaging the gear 13 and being provided with a noncircular central aperture to permit of the pinion being turned.

by a plug-wrench; 15, a lock illustrated as a combination lock secured to the rear of the front portion of the door, the door having a deep circular recess in its rear; 16, the 5 knob of the combination lock, the same being disposed in front of the gear-casing, which gear-casing has a removable front plate; 17, a tube surrounding the spindle of the combination lock and having its rear 10 end secured in the front of the door 5, the front end of this tube extending to near the rear surface of the gear-casing; 18, an escutcheon plate centrally pivoted to the front plate of the gear-casing and of such diameter 15 as to extend beyond the axis of the knob of the combination lock, the front portion of the spindle of the combination lock being journaled in this escutcheon plate; 19, a segmental slot formed in the front plate 20 of the gear-casing, concentric with the axis of the door, the spindle of the combination lock passing through this slot, and the slot being of such segmental extent as to permit the door and the spindle of the combination 25 lock to turn to such angular extent as is necessary in permitting the door to be turned so as to engage its lugs with the lugs of the door-jamb; 20, the spindle of the combination lock; 21, a pawl mounted in a 30 mortise in portion 4 of the door and adapted to lie in inner position, as seen in Fig. 13, or be swung outwardly by the combination lock in front of one of lugs 4 in the door-jamb when the door has been seated 35 and turned; 22, a plate of machineable metal secured to the front surface of the door, it being assumed that the door will be of un-machineable metal, such as cast manganese steel, this plate 22 facilitating the securing 40 of journal 12 and gear 13 to the door; 23, the pivot uniting escutcheon plate 18 with the front plate of the gear-casing, the axis of this pivot coinciding with the axis of the door; and 24, the noncircular aperture in 45 pinion 14 to receive the plug of the wrench employed in turning the door.

The door features and jamb features thus far referred to pertain to the lug door component of our compound door, and all of 50 the features thus far referred to are or may be of the form and mode of operation common in circular lug door construction. While the operation of such circular lug doors is well understood by those skilled in 55 the art, it may be stated that, the door standing open, it is to be pushed to closed position, the lugs on the door passing between the lugs in the door-jamb. Then, by turning pinion 14, the door is to be given the 60 fraction of a revolution in the door-jamb so as to bring the door-lugs behind the jamb-lugs, the helical character of the contacting surfaces of the lugs drawing the door home tightly. The amount of angular motion to 65 be given to the door will be dependent on

the number of the lugs in the circumferential series. In the illustration the door-jamb carries a series of four lugs, and the door carries a series of four lugs, and consequently an eighth of a turn given to the door will bring the door-lugs in behind the jamb-lugs. The combination lock may now be manipulated, throwing the pawl 21 outwardly so that its free end will engage the trailing end of one of the jamb-lugs thus preventing the turning back of the door to disengage the lugs. Such closing and securing of the door would be that employed for day locking, though for more perfect security the door, as thus far described, could be provided, in addition to the combination lock, with a time lock to throw another locking pawl or to dog the pawl thrown by the combination lock. But in our improved construction, which we will now describe, we employ an inner door and place the time lock on the inner door thus rendering an employment of the time lock on the outer door much less essential than if the door were single instead of compound, though of course, a time lock may be employed upon the outer door also.

Now, understanding that the safe has a circular door-opening provided with lugs and adapted to be closed by means of a lugged door turned a small fraction of a rotation, and then locked against being turned backward, we proceed with the drawings.

25, indicates a portion of the door-jamb inward of and concentric with the portion engaged by the door-lug, this inward portion of the door-jamb being provided with a thread adapted for a screw-door; this screw portion of the jamb being tapered as is usual in screw-door safes; 26, a screw-door adapted to screw into and tightly fit the screw portion of the jamb and to be seated home by substantially one rotation; 27, a cylindrical recess in the rear of the lug-door concentric with the axis of the lug-door and of a diameter equal at least to the greatest diameter of the screw-door; 28, a cylinder formed with or rigidly secured to the rear of the screw-door and fitting the recess in the lug-door, this cylinder being adapted to turn and slide in the recess of the lug-door and being itself provided with a recess at its front; 29, a central noncircular socket at the front of the screw-door, the illustration showing this socket as being formed in one structure with the cylinder 28; 30, a spindle journaled centrally in the lug-door and having at its rear a noncircular portion fitting and capable of sliding in socket 29 of the screw-door, this spindle projecting in the front of the lug-door; 31, a collar on spindle 30 to prevent the endwise movement of the spindle relative to the lug-door; 32, a circular socket

rigidly secured to the rear of the lug-door and adapted to receive the circular socket-boss at the rear of the screw-door; 33, a gear mounted in gear-casing 8 concentric with the axis of the bearings; 34 an arm projecting inwardly from this gear and engaging the front end of spindle 30, this gear being journaled within journal 12 of the lug-door, so that the gear and arm and spindle may turn independent of the lug-door, the arm being of such width that it may make at least seven-eighths of a turn, relative to the lug-door without being interfered with by the spindle of the combination lock; 35, a pinion journaled in the gear-casing and engaging gear 33, the illustration showing this pinion as having its axis coincident with that pinion 14 employed in turning the lug-door; 36, a noncircular aperture in pinion 35, of the same form as aperture 24 in pinion 14 so that the same plug-wrench may engage and operate the two pinions simultaneously; 37, a time lock on the inner portion of the screw-door, the screw-door being illustrated as recessed at its rear to receive a portion of the time lock; 38, an escutcheon plate surrounding the time lock and closing the recess in the rear of the screw-door; 39, a plate of machineable metal rigidly secured to the rear face of the lug-door to facilitate the attachment of parts if the lug-door be of non-machineable metal; 40, (Fig. 2) a pawl pivoted in the root of the rearmost thread of the screw-door and adapted to be held outwardly by the time lock, and engaging the rear end of the thread of the screw-portion of the door-jamb as is usual in safes having doors of screw type; 41, a radial pin rigidly held in the recess in the lug-door; and 42, a helically trending notch in cylinder 28 adapted to engage pin 41 when the cylinder 28 just approaches complete retraction within the recess of the lug-door.

45 Assume the door standing open with the screw door telescoped back within the lug-door, as indicated in Fig. 3. If, now, the lug-door be in such angular position that it may freely enter the door-jamb, the compound door may be closed and, by applying the plug-wrench in both pinions, the lug-door may be given the eighth of a turn necessary to bring about the proper engagement of the lug, and the combination lock may be thrown. This securely locks the safe so far as the lug component of the compound door is concerned and this would be the performance for ordinary day locking. In this performance the screw-door has taken no part for it has simply ridden idly with the lug-door within which it is telescoped, though the eighth turn which has been given to the lug-door has incidentally been given to the screw-door.

65 If, now, it be desired to completely utilize

the compound-door the plug-wrench is partially withdrawn so as to engage only with pinion 35, whereupon the screw-door may be screwed home, the lug-door being already home, and the time lock, at the proper time, 70 may throw its pawl and lock the screw-door.

When it is time to open the completely locked safe the plug-wrench is applied to pinion 35 and, the time lock having gone off guard, the screw-door may be withdrawn 75 from its seat and telescoped back into the door lug after which, the lug-door having been unlocked, the plug-wrench may be inserted further so as to engage pinion 14, whereupon the lug-door may be given its 80 eighth turn to release its lugs so that the compound door may be opened, the screw-door riding idly in the lug-door. When the compound door is standing open, or when it is closed, and the screw-door has not been 85 screwed into its seat, the screw-door is simply idly supported by the lug-door, and in the absence of preventive means, the screw-door may shift its position in the lug-door, or, when the compound door was standing 90 open, the screw-door could be pulled bodily out of the lug-door within which it is telescoped. It is desired that when the compound door is pushed to closed position the angular relationship of the two doors relative to each other and relative to the lugs and threads in the jamb be such that there will be no interference of parts when the compound door or either of its components is turned. It is for this purpose that we 100 provide pin 41 and slot 42. Both components of the door being completely home, the first action is the unscrewing of the screw-door from its jamb and the telescoping of that door back into the lug-door. At 105 just about the completion of this unscrewing operation of the screw-door the notch 42 engages pin 41, and when the unscrewing and telescoping is completed the screw-door is held in definite angular relationship to the 110 lug-door and cannot move rearwardly from it except by rotary motion of the screw-door relative to the lug-door, thus preventing any shifting of the screw-door relative to the lug-door in an axial direction as the result 115 of momentum in closing the compound door. When the screw-door is to be put into service then the earliest fraction of its rotation relative to the lug-door disengages it from pin 41 leaving the screw-door quite free to 120 slide rearwardly within the lug-door. It will thus be seen that as the screw-door completes its telescoping into the lug-door it does so by a screw action, the pin and notch 125 representing the two elements of the screw so that this screwing feature becomes effective only at near the completion of the inward telescopic action and at the beginning of the outward telescopic action.

In the exemplification herein shown, is a 130

construction in which a complete homing of the compound door is effected by a complete rotation, the first eighth turn completely homing the lug-door and giving to 5 the screw-door an eighth turn, while seven-eighths of a turn farther given to the screw-door alone completes its homing. These values will of course be changed if the number of lugs in the circular series be changed 10 or if the pitch of the thread be changed.

In the exemplification herein shown the two pinions are mounted with their axes coincident, so that a plug-wrench may operate upon the outer one alone or upon both 15 simultaneously. This is desirable but not at all essential, as the pinion for turning one component of the door may have one position and the pinion for turning the other component of the door may have an entirely 20 different position, a condition which would, of course, require that the tool employed for turning the pinions should operate first upon one of them and then be shifted to operate upon the other, or else that each 25 pinion be provided with an operating tool.

While, for facility in description, the term "Safe" has been used, it is to be understood that that term is to include not only such portable structures generally designated as 30 safes but also such larger fixed safe structures as are generally designated as vaults. In vaults the door sometimes closes an opening directly in the front wall of the vault, while in other cases it is employed in closing an 35 opening in the front wall of a vestibule projecting from the vault. It is to be understood that our invention is to be considered regardless of whether the safe be a small 40 safe-structure, or a large vault-structure, or whether the door-opening be directly in the front of the structure or in a vestibule added to the general structure.

It is furthermore to be understood that the structure illustrated and described constitutes but a single exemplification of our 45 invention. We have sought to set forth the principle of our invention and the best mode in which we at present contemplate embodying that principle.

50 We claim:—

1. A compound round safe door comprising, a lugged door-component, a threaded door-component mounted rotatably and slidably upon the lugged component, a hinged support for the door, and means for rotating the two door-components independently, combined substantially as set forth.

2. A compound round safe door comprising, a lugged door-component, a threaded door-component mounted rotatably and slidably upon the lugged component, a hinged support for the door, means for rotating the two door-components independently, independent locks on and controlling the door-components to prevent their rotation, and

means for preventing the rotation of one of the door-components until the other door-component has been unlocked, combined substantially as set forth.

3. A compound round safe door comprising, 70 a lugged door-component, a threaded door-component mounted rotatably and slidably upon the lugged component, a hinged support for the door, means for rotating the two door-components independently, a time 75 lock on and controlling the threaded door-component, a combination lock on and controlling the lugged door-component, and means to permit the turning of the lugged door component only after the time-lock has 80 released the threaded door-component to permit its turning, combined substantially as set forth.

4. A compound round safe door comprising, 85 a lugged door-component, a threaded door-component mounted rotatably and slidably upon the lugged component, a hinged support common to the two door-components, means for rotating the lugged door-component 90 in the hinged support, a spindle journaled in the lugged door-component and connected with the threaded door-component, and means for turning said spindle from the exterior of the door to serve in turning the threaded door-component independently of 95 the lugged door-component, combined substantially as set forth.

5. A compound round safe door comprising, 100 a lugged door-component, a threaded door-component mounted rotatably and slidably upon the lugged component, a hinged support common to the two door-components, a bearing carried by the support, a journal on the lugged door-component to 105 operate with the bearing, a gear fast on the outside of the lugged door-component, a pinion journaled in said support and engaging said gear, a spindle journaled in the lugged door-component and operatively connected with the threaded door-component, 110 and means for turning said spindle and pinion at the outside of the lugged door-component, combined substantially as set forth.

6. A compound round safe door comprising, 115 a lugged door-component, a threaded door-component mounted rotatably and slidably upon the lugged component, a hinged support common to the two door-components, a bearing carried by the support, a journal on the lugged door-component to 120 operate with the bearing, a gear fast on the outside of the lugged door-component, a pinion journaled in said support and engaging said gear, a spindle journaled in the lugged door-component and operatively connected 125 with the threaded door-component, means for turning said pinion at the outside of the lugged door-component, a second gear mounted for rotation on the outer side of the lugged door-component and operatively con- 130

nected with said spindle, a second pinion journaled in said support and engaging said second gear, and means for turning said pinions, combined substantially as set forth.

5 7. A compound round safe door comprising, a lugged door-component, a threaded door-component mounted rotatably and slidably upon the lugged component, a hinged support common to the two door-components, a bearing carried by the support, a journal on the lugged door-component to co-operate with the bearing, a gear fast on the outside of the lugged door-component, a pinion journaled in said support and engaging 10 said gear, a spindle journaled in the lugged door-component and operatively connected with the threaded door-component, means for turning said pinion at the outside of the lugged door-component, a second gear mounted for rotation on the outer side of the lugged door-component and operatively connected with said spindle, a second pinion journaled in said support and engaging said second gear, and means for turning said 15 pinions, said two pinions having their axes in a common line whereby they may be turned simultaneously by an agent in common, combined substantially as set forth.

20 8. A compound round safe door comprising, a lugged door-component, a threaded door-component mounted rotatably and slidably upon the lugged component, a hinged support common to the two door-components, a bearing carried by the support, a journal on the lugged door-component to co-operate with the bearing, a gear fast on the outside of the lugged door-component, a pinion journaled in said support and engaging said gear, a spindle journaled 25 in the lugged door-component and operatively connected with the threaded door-component, means for turning said pinion at the outside of the lugged door-component, a second gear mounted for rotation on the outer side of the lugged door-component, a combination lock-spindle projecting through the lugged door-component and within said second gear, an arm projecting from the rim of said second gear into operative connection with said spindle, a second pinion journaled in said support and engaging said second gear, and means for turning said pinions, combined substantially as set forth.

30 9. A round door safe comprising, a rotary door, a hinged support for the door, a journal uniting the door and support, a non-rotary gear-casing carried by said support and provided with a segmental slot, gearing within said casing for turning said door, a lock spindle projecting from the door and through said segmental slot, combined substantially as set forth.

35 10. A compound round safe door comprising, a lugged door-component having a frusto-conical periphery, a threaded door-

component having its greatest diameter less than the least outer diameter of the lugged door mounted rotatably and slidably upon the lugged component and having a frusto-conical periphery, a hinged support common 70 to the two door-components, and means for rotating the two door-components independently, combined substantially as set forth.

11. A compound round safe door comprising, a lugged door-component having a cylindrical recess in its rear face, a threaded door-component at the rear of the lugged component, a cylindrical extension on the front of the threaded component adapted to 75 turn and slide in said recess, a hinged support for the door, and means for rotating the two door-components independently, combined substantially as set forth.

12. A compound round safe door comprising, a lugged door-component having a cylindrical recess in its rear face, a threaded door-component at the rear of the lugged component, a cylindrical extension on the front of the threaded component adapted to 80 turn and slide in said recess, a hinged support common to the two door-components, means for rotating the two door-components independently, a substantially radial pin fixed within said recess in the path of the 85 cylindrical extension, and a helically trending notch in the rear of said extension and adapted to engage said pin as the threaded component approaches the end of its motion of retraction within the lugged component, combined substantially as set forth.

13. A compound round safe door comprising, a lugged door-component having a cylindrical recess in its rear, a threaded door-component at the rear of the lugged component, a cylindrical extension on the front of the threaded component and adapted to turn and slide in said recess, a spindle centrally journaled in the lugged component and having a noncircular rearward extension, a noncircular socket carried by the threaded component and slidably engaging said spindle, and a single hinged support for said two door-components in common, combined substantially as set forth.

14. A compound round safe door comprising, a lugged door-component having a cylindrical recess in its rear and formed of non-machinable metal, a disk of metal rigidly secured to said lugged component at the 110 front wall of said recess, a threaded door-component of metal, a cylindrical extension of metal secured to said threaded component and mounted to turn and slide within said cylindrical recess, and means for rotating the two door-components independently, combined substantially as set forth.

15. A compound round safe door comprising, a threaded door-component adapted to be seated in a threaded door-jamb by a given 115

degree of rotation, a lugged door-component adapted to be seated in a lugged door-jamb by a given degree of rotation, means connecting the two door-components so that the threaded component may turn and slide in relation to the lugged component, a hinged support for the lugged component, means operable from the exterior of the door for turning the threaded component through a portion of the rotation necessary to seat it, and means for turning the lugged component in the hinged support to bring about the seating of the lugged component, the means for turning the threaded component and lugged

component being operable in unison so that 15 as the lugged component turns to seating position the threaded component completes its turning, combined substantially as set forth.
